United States Patent Office

Des. 219,805
Patented Feb. 2, 1971

219,805

PACKAGING CONTAINER

André Courréges, Neuilly, France, assignor to Courréges Parfums, Paris, France

Filed Jan. 23, 1970, Ser. No. 21,043

Term of patent 14 years

Int. Cl. D9—04

U.S. Cl. D9—237

FIG. 1

FIG. 2

FIG. 4

FIG. 1 is a perspective view of a packaging container showing my new design,

FIG. 2 is a front elevation view thereof,

FIG. 3 is a side elevation view thereof, and

FIG. 4 is a top plan view thereof.

In each figure the hidden side is identical with the one seen.

I claim:

The ornamental design for a packaging container, as shown and described.
